UNITED STATES PATENT OFFICE.

ALEXANDER J. McDONALD, OF CHICAGO, ILLINOIS.

RAILWAY-GATE.

SPECIFICATION forming part of Letters Patent No. 404,724, dated June 4, 1889.

Application filed July 10, 1888. Serial No. 279,562. (No model.)

To all whom it may concern:

Be it known that I, ALEXANDER J. McDONALD, a citizen of the United States, residing at Chicago, in the county of Cook and State of Illinois, have invented certain new and useful Improvements in Railway-Gates, of which the following is a specification.

My invention relates to certain improvements in railway-gates wherein the swinging arms are connected or tied to each other by underground cables, by means of which both gates are simultaneously operated from a single power-engine; and my invention consists in providing hinged casings for the metallic tie-rods or anchors, whereby the contraction or expansion of said rods, owing to changes of temperature, may be compensated for and a uniform movement and operation of the gates secured under all conditions.

In the accompanying drawings, Figure 1 is a vertical section through the posts of swinging railway-arms, shown in side elevation, and showing; also in side elevation, other parts connected to said swinging arms and the conduits for the cables. Fig. 2 is a plan view of the lower portion of one of the gate-posts, and showing therein certain of the operating parts. Figs. 3 and 4 are views in side elevation of a combined sheave-covering and cable-guard, which is shown provided with a hinge in Fig. 3 near its upper end, and in Fig. 4 midway of its vertical height, whereby it is adapted to be pivotally secured to a fixed part of the gate. Fig. 5 is a view in elevation, partly in vertical section, through the sheave-covering and cable-guard, the sheave being shown partly in section, located within the lower portion of the structure. Fig. 6 is a vertical section transversely of the cable-guard and through the sheave-guard and sheave. Fig. 7 is a detail showing a method of carrying the cable-conduits across the street.

In the drawings, 8 represents one of the gate-posts upon which the pivoted gate-arm 9 is supported. 10 is the rock-shaft for said pivoted arm; 11, a cross-bar secured rigidly midway of its length to the rock-shaft 10. Cables 12 13 are connected to the respective ends of the cross-bar 11, and are carried under sheaves—such as 16, Figs. 5 and 6—located

below the gate-post, and are thence conducted through conduits, which may be iron tubes or pipes 14 15, across the street, around other sheaves located below a gate-post 8^a, and thence upward, where they are secured to the respective ends of a cross-bar 11^a, which in turn is fixed upon the rock-shaft 10^a, and to which rock-shaft is secured a second gate-arm 9^a.

It will be understood that the parts above described are duplicated on either side of the street.

Within the gate-post 8 and toward its bottom is located a power-cylinder 17, the piston 65 of which operates through a suitable connecting medium to rock the shaft 18, and with it cross-bar 19, and this latter is connected by the links 20 with the cross-bar 11, whereby movement is imparted to the gate-arm 9, and 70 by means of the cables 12 13 to the gate-arm 9^a.

The metallic conduits 14 15 may be of gas-pipe, and are preferably connected by screw-threads, as shown in Fig. 5, to a casting 21, 75 which is hollowed out to receive the sheaves 16. This casting 21 has a removable face 22, which is secured by bolts 23, and thereby the removal and insertion of the sheaves 16 are readily effected. These sheaves are located 80 below the level of the surface of the pavement, and therefore are subject, as before mentioned, to be entirely surrounded by the water which collects in the pit beneath the gate-post. I therefore employ this closed 85 sheave-guard, and prefer to use a packing at the joint between the removable face 22 and the stationary portion 21 to prevent water from entering. The sheave-guards have an upwardly-extending projection in the form 90 of a hollow casting 23^a, with, preferably, a flaring mouth 24 so far above the level of the pavement that all danger of water finding ingress to the cable and sheaves is obviated. It will thus be seen that a continuous conduit 95 is provided by the pipes 14 15 and sheave-coverings and extensions 23^a, so that the cable and sheaves 16 are entirely protected from water.

To compensate for the shortening of the 100 pipes 14 15 by contraction and for their lengthening by expansion, owing to changes

in temperature, I hinge the extensions 23^a and the sheave-covering to one of the gate-posts. This may be done as shown either in Fig. 3 or in Fig. 4, in both of which 28 represents the hinge, and 29 a fixed part of the gate-post structure. A slight movement of these parts, due to the expansion or contraction of the metallic conduits 14 15, is permitted by the hinge 28 without affecting the operation of the cables 12 13 or the joints and connections, and by the use of these hinged parts the uniform operation of the gate-arms is secured. It may be found expedient to fill the sheave-coverings and the conduits 14 15 with oil to secure the constant lubrication of the sheaves and cables. Fig. 7 illustrates the method of laying the conduits 14 15 in the street. In

said figure, 25 represents a timber laid as foundation for paving-blocks 26, resting upon said timber. The timber 25 is channeled, as 20 at 27, and the pipes 14 15 are laid in said channel.

I claim—

In a railway-gate, the combination, with a fixed part of the gate structure, of a cable guard 25 or covering hinged thereto and adapted to support a sheave for the cable, and a conduit-pipe connected rigidly to said guard or covering, substantially as described.

ALEXANDER J. McDONALD.
